Atty.

UNITED STATES PATENT OFFICE.

MARTIN HILGERS, OF TAZEWELL COUNTY, ILLINOIS.

RESPIRATING DEVICE.

1,210,939.

Specification of Letters Patent. Patented Jan. 2, 1917.

Application filed June 24, 1914. Serial No. 847,167.

To all whom it may concern:

Be it known that I, MARTIN HILGERS, citizen of the United States, residing in the county of Tazewell and State of Illinois, have invented certain new and useful Improvements in Respirating Devices; and I do hereby declare that the following is a full, clear, and exact description of the invention, which will enable others skilled in the art to which it appertains to make and use the same.

This invention relates to a respirating device used while massaging the face or treating the eyes, being adapted to permit the user to breath while the face is submerged or while being treated with vapors.

The invention relates more particularly to a respirating device of peculiar construction that can be constructed at a low cost, and any one of whose parts when broken or damaged can be replaced at little expense and without requiring the purchase of an entirely new one.

One of the objects of the invention is to provide a mouth piece of peculiar form around which the lips of the wearer can be tightly closed so as to prevent entrance of the fluid or vapors in the mouth.

Another object is to provide a structure including a mouth piece and integral means for closing the nostrils for preventing the passage of fluid into the nose.

In the accompanying drawing forming a part of this application, Figure 1 is a rear elevation of my invention, and Fig. 2 is a side elevation of the same showing its adjustment when in use.

A indicates a hollow body preferably of hard rubber including two opposite extensions or horns B provided with end apertures C, but one of which is shown, and an open mouth piece D flared at its outer free end so that its said mouth will be of a greater diameter than the main portion or neck of the device. The extensions or horns B are preferably enlarged at E so that they will receive and retain a flexible tube F. Each of the latter has secured in any suitable manner at its outer end a bow G adapted to be placed over and held upon the ears of the patient.

Secured to or formed integral with the body A is an extension H, Fig. 2, which terminates in two spaced extensions J, Fig. 55 1, so disposed with reference to the mouth piece as to receive the nose of the patient

between them so as to close the nostrils, the mouth piece being held in the mouth with the lips tightly closed around the said neck thereof.

My device differs from others, of which I am aware in that the flaring mouth piece is provided over which the teeth and lips can be placed, the lips being firmly held around the neck of the mouth-piece, guarding against leakage of the fluid or vapors into the mouth.

Devices of which I am aware do not include as an integral part of the structure means for closing the nostrils and to this feature I attach importance together with the flaring mouth piece, and the construction of a device of separable parts any one of which may be replaced.

It is necessary at times to keep the face submerged at long intervals as in the treatment of the eyes, for example, and a device of this nature is necessary and it includes all of the advantages named in a single or one piece article.

I may not employ the tubes F or the portion G but may extend the parts B so as to be substantially of the length of the said parts F. The patient in this case can hold the device in position by means of the teeth and lips so that the ends of B will be above the surface of the fluid.

Having thus described my invention, I claim:

1. In a respirating device for use in treating affections of the eye, the combination of an open tubular mouth-piece including a tubular extension communicating with it and extending away from it at an angle to the axis of its bore, means attached to the said extension adapted to be engaged or hooked over the ear of the patient, and a pair of members extending from the said mouth-piece to engage over the nose of the patient and adapted by their form, in conjunction, to close the nostrils.

2. In a respirating device for use in treating affections of the eye, the combination of a tubular mouth-piece open at one end, a tubular member with which it communicates at its other end, said tubular member extending at each side of the said mouth-piece, the resulting extensions lying in a plane disposed at an angle to the axis of the mouth-piece, the axis of the bore of the latter piercing said plane, means extending from the said extensions to sus-

pend them from the ears of the patient, and a pair of extensions carried by the mouth-piece to engage each side of the nose of the patient and adapted by their form, in conjunction, to hold the nostrils closed.

3. As a new article of manufacture, a U-shaped tubular body having a substantially centrally disposed, hollow, communicating, outwardly flared, extension open at its outer end lying between the arms of

the U-shaped body, a pair of spaced extensions formed with said centrally disposed extension, and a tubular portion extending from each arm of the said body each including a looped portion at its free extremity. 15

In testimony whereof I affix my signature, in presence of two witnesses.

MARTIN HILGERS.
